UNITED STATES PATENT OFFICE.

JOHN M. NEUERT, OF INDIANAPOLIS, INDIANA.

STREET-SWEEPING MACHINE.

Application filed October 20, 1924. Serial No. 744,707.

To all whom it may concern:

Be it known that I, JOHN M. NEUERT, a citizen of the United States, residing at Indianapolis, in the county of Marion and State of Indiana, have invented certain new and useful Improvements in a Street-Sweeping Machine, of which the following is a specification.

This invention relates to improvements in street sweeping machines and has for its principal object to provide a means for efficiently sweeping the gutters.

One of the important objects of the present invention is to provide a street sweeping machine of the above-mentioned character, wherein means is provided for gathering up the refuse lying in the gutters, additional means being provided for cooperation with the aforementioned means whereby the collected refuse is left in piles at spaced intervals in the gutters, thus enabling the refuse to be easily and readily removed from the gutters.

A further object of the invention is to provide a street sweeping machine of the above mentioned character, wherein scraping means is arranged forwardly of the refuse gathering and pile forming means for moving the refuse into the path of the gathering means.

A further object of the invention is to provide a street sweeping machine of the above-mentioned character, wherein means is provided for rendering the same inoperative especially when the machine is turned around and further when not in use.

A still further object is to provide a street sweeping machine of the above-mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a top plan view of the street sweeping machine embodying my invention.

Figure 2 is a bottom plan view thereof.

Figure 3 is a side elevation.

Figure 4 is a sectional view taken approximately on line 4—4 of Figure 1. 55

Figure 5 is a sectional view taken approximately on line 5—5 of Figure 1.

Figure 6 is an enlarged detail side elevation of the rear end of the auxiliary frame showing the rear brush in an inoperative 60 position.

Figure 7 is a detail perspective view of the gutter scraper, and

Figure 8 is a sectional view taken approximately on line 8—8 of Figure 5. 65

In the drawings, wherein for the purpose of illustration is shown the preferred embodiment of my invention, the numeral 1 designates the main frame of my improved street sweeping machine, the forward end thereof being supported on the front wheels 2 and the rear end on the rear wheels 3 whereby the machine is rendered portable. The machine is adapted to be attached to the rear of a tractor or the like (not shown) 70 when in operation. An auxiliary frame designated generally by the numeral 4 is hingedly supported on the rear portion of the main frame 1 and the same includes the angle iron side members 5 and 6 respectively which are hingedly secured at their forward ends to the respective sides of the main frame 1 adjacent the rear end thereof as indicated at 7 and 8 respectively in the drawings. An angle-iron cross bar 9 extends 80 transversely across the outer ends of the side members 5 and 6. 85

The ends of the cross bar 9 extend beyond the rear ends of the side members 5 and 6 and provide a means for supporting the rear ends of the brackets 10 and 11 respectively, the latter being secured at their forward ends to the side members 5 and 6 and being arranged in spaced relation thereto in the manner more clearly illustrated in Figure 1. The bracket 11 is of greater length than the bracket 10 as is also clearly illustrated in Figures 1 and 2 of the drawings. Secured at their upper edges to the outer sides of the brackets 10 and 11 respectively are the metallic plates 12 and 13 respectively. A similar metallic plate 14 extends transversely across the rear end of the auxiliary frame 4 and is hingedly connected at its upper edge to the cross bar 9 in the manner as illustrated at 15. Supported on the

inner opposed faces of the side plates 12 and 13 and extending for substantially the full length thereof are the brush heads 16 and 17 respectively, the bristles 18 and 19 extend from the bottoms of the brush heads 16 and 17 respectively and protrude below the lower edges of the side plates. A similar brush head 20 is disposed on the inner face of the rear plate 14 and the bristles 21 thereof also extend from the bottom of the brush head and protrude below the lower edge of the rear plate 14 for cooperation with the side brushes 18 and 19.

Each of the brush heads is adapted for vertical adjustment on its respective supporting plate by means of the L-shaped brackets 21, a pair of such brackets being associated with each brush head. The shorter arm of each of the brackets is secured to the top of the brush heads as illustrated at 21' while the longer arm of each of the L-shaped brackets is slotted as illustrated at 23 for cooperation with the bolts 24 which extend through each of the plates. In this manner the brushes or bristles may be raised or lowered to any desired height. The brushes 18, 19 and 21 respectively cooperate to provide a refuse collecting hopper or chamber 25.

For the purpose of normally holding the rear plate 14 and the brush head 20 carried thereby in operative relation with respect to the side brushes, I provide the spring catches 26 on the respective side plates 12 and 13, the heads 27 of the spring catches being in engagement with the angle iron members 28 secured to the respective ends of the rear plates 14 in the manner as clearly illustrated in Figure 1 of the drawings.

The spring catch releasing means comprises a pair of angular levers 29 and 30, the vertical portions of which are supported in the brackets 31 and 32 secured to the side plates 12 and 13 respectively. The lower ends of the vertical portions of the angular levers 29 and 30 are provided with the lateral extensions 33 and 34 respectively, the same being normally disposed between the spring catches and the side plates in parallel spaced relation thereto as is clearly illustrated in the drawings.

The horizontally disposed portions of the angular levers 29 and 30 extend inwardly over the cross bar 9 of the auxiliary frame 4 and are connected at their inner ends to the outer ends of the rods 35 and 36 respectively, the latter extending forwardly across the top of the auxiliary frame and being secured at their forward ends to the outer ends of the crank lever 37 which is journaled in a suitable support provided therefor on the rear portion of the main frame 1 as shown at 38 with reference more particularly to Figures 2 and 3 of the drawings. An elongated rod 39 is connected at its rear end to the intermediate portion of the crank

lever 37 and the forward end of the rod has associated therewith a suitable foot actuated lever 40 which is supported on a suitable platform 41 secured to the top of the main frame 1 adjacent the forward end thereof. It is obvious from the construction above described that when the foot lever 40 is depressed, the angular levers 29 and 30 will have their vertical portions rotated in the supporting brackets provided therefor on the side plates whereby the lateral extensions 33 and 34 will engage the spring catches and cause the heads thereof to become disengaged from the respective ends of the rear plate 14 in order to permit the upward swinging movement of the rear plate and the brush carried thereby in the manner to be presently described.

The means for raising the rear plate 14 comprises a bifurcated arm 42 which is supported at its lower end on the intermediate portion of the cross bar 9 and extends upwardly therefrom at an incline. A bell crank lever 43 is pivotally supported in the bifurcated end of the arm 42 as illustrated at 44, one end of said bell crank lever being secured to a suitable lug 45 provided on the outer face of the rear plate 14 through the medium of the link 46. The other free end of the bell crank lever 43 is pivotally connected to the rear end of an elongated rod 47 which extends longitudinally on the auxiliary frame and the main frame and is connected at its forward end to the lower end of a hand lever 48. The hand lever 48 is pivotally supported adjacent its lower end on the bolt 49 which extends transversely through suitable registering openings provided in the upper ends of a pair of spaced brackets 50 and 51 respectively. These brackets are also secured to the platform 41 in the manner clearly illustrated in Figures 1 and 3 of the drawings.

A pair of longitudinally extending angle irons 52 and 53 respectively are arranged between the sides of the main frame 1 and the rear ends of these longitudinal angle irons extend beyond the rear end of the main frame. A crank lever 54 is journaled across the top of the rear ends of these angle irons and the free ends of the arms 55 and 56 of the crank lever 54 are pivotally secured to suitable lugs 57 and 58 which extend upwardly from the angle iron cross bar 59 which extends transversely across the side members 5 and 6 of the auxiliary frame 4 forwardly of the aforementioned cross bar 9.

An arm 60 extends upwardly from the intermediate portion of the crank lever 54, the upper end thereof is provided with an enlarged eye through which extends the rear end of an elongated rod 61. A cotter pin 62 extends through a suitable opening provided in the rear end of the rod 61 on one side of the apertured arm 60 and a similar

cotter pin 63 extends through a suitable opening provided in the intermediate portion of the rod at a point adjacent the upper end of the arm 62. A coil spring 64 encircles the rod 61 and is disposed between the arm 62 and the cotter pin 63 in the manner clearly illustrated in Figure 1 of the drawings.

The forward end of the elongated rod 61 is pivotally connected to the lower end of a suitable hand lever 65 which is also pivotally supported adjacent its lower end on the bolt 49. For the purpose of holding a hand lever 65 in any desired position so that the auxiliary frame 4 may be held in inoperative position at any desired angle, I provide the upper edge of the supporting bracket 50 with the segmental teeth 66, a suitable pawl 67 carried by the lever 65 being adapted for cooperation with the teeth 66. An auxiliary lever 68 is associated with the upper free end of the hand lever 65 and provides a means for controlling the engagement of the pawl 67 with respect to the teeth 66.

Pivottally supported at their forward ends on the intermediate portions of the angle irons 52 and 53 are the arms 69 and 70 respectively. The rear ends of the arms are curved downwardly and support thereon the scraper 71, the latter being disposed substantially transversely with respect to the main frame 1 and being further located forwardly of the refuse collecting hopper 25. A blade 72 is secured to the lower edge of the scraper 71 for engagement with the surface of the ground over which the machine travels and the purpose of this scraper is to provide a means whereby the refuse lying in the street adjacent the curb or gutter may be moved into the path of the brushes forming the refuse receiving hopper. Hangers 73 and 74 are provided for the intermediate portions of the arms 69 and 70 and are secured at their upper ends to the longitudinal angle irons 52 and 53 and the adjacent portions of the sides of the main frame 1.

The scraper 71 is adapted to be raised to an inoperative position through the medium of a link 75 which is secured at its lower end to the scraper and at its upper end to one end of a suitable bell crank lever 76 which is pivoted at 77 on the main frame. A rod 78 is secured at its rear end to the other free end of the bell crank lever and extends forwardly on the main frame, the same being secured at its forward end to the lower end of a hand lever 79 which is also pivotally supported on the platform 41. A segmental rack 80 is arranged on the platform 41 for cooperation with the pawl 81 which is associated with the hand lever 79 and an auxiliary handle 82 is provided for disengaging the pawl 81 from the segmental rack 80 to permit the free swinging movement of

the lever 79. The segmental rack and locking pawl permits the scraper 71 to be held in any desired adjusted position.

A gutter scraper forming a part of the present invention is illustrated at 83, a blade 84 being secured to the lower edge thereof. Carried by the rear face of the scraper 83 are a pair of vertically extending T-shaped members 85, the same being adapted for slideable engagement with the guides 86 provided therefor on the scraper supporting plate 87 whereby the scraper is adapted for vertical slideable movement with respect to the plate 87 in the manner to be presently described. A means for raising and lowering the scraper 83 with respect to the supporting plate 87 comprises a crank lever 88 which is journaled in suitable bearings provided therefor on the platform 41, the ends of the arms of the crank lever being connected to the ears 89 formed on the upper edge of the scraper 83 adjacent the respective ends thereof by means of the links 90. An operating lever 91 is associated with the crank lever 88 and the same extends upwardly from one end thereof. A segmental rack 91 is mounted on the platform 41 adjacent the lever 90 and cooperating therewith is the pawl 92 which is carried by the lever 90 for holding the latter and the scraper 83 in any desired adjusted position. An auxiliary handle 93 is associated with the upper end of the lever 90 for releasing the pawl 92 from engagement with the segmental teeth 91 to permit the raising and lowering of the scraper with respect to the supporting plate 87.

The supporting plate 87 is carried by the carriage designated generally by the numeral 94 through the medium of the depending arms 95. The carriage 94 is adapted for lateral sliding movement with respect to the main frame for moving the supporting plate and the scraper 83 carried thereby laterally and to this end, the carriage includes the angle irons 96 and 97 and the substantially T-shaped member 98 which is disposed intermediate the angle irons 96 and 97 and is secured in parallel spaced relation thereto by the cross strips 99. The angle irons 96 and 97 are adapted for slideable movement on the transversely extending angle irons 100 and 101 respectively, the latter extending transversely across the bottom of the intermediate portion of the main frame 1. The T-shaped member 98 is adapted for slideable movement in the guide members 102 and 103 which are secured at their ends to a cross strip 104 which extends transversely across the angle irons 100 and 101.

The angle irons 96 and 97 and the T-shaped member 98 are adapted to move in unison and this is accomplished by having the inner end of the T-shaped member 98 extending beyond the inner ends of the angle

irons 96 and 97 and being connected thereto by the fastening members 105, the latter converging and terminating in an upstanding member 106 which is pivotally connected to 5 one end of a bar 107, the latter extending longitudinally over the carriage and being connected at its other end to the lower end of a hand lever 108. The latter extends through a suitable opening provided there- 10 for in the platform 41 adjacent the side of the main frame and is pivotally supported at 109 between a pair of lugs 110 and 111 secured to the upper surface of the platform 41. By actuating the lever 108, the carriage 15 94 is adapted to move transversely across the bottom of the main frame whereby the supporting plate and the scraper mounted thereon may be moved into and out of engagement with the gutter.

20 A seat 112 is provided on the platform 41 whereby an attendant may have control of the several hand levers and the foot lever for actuating the several parts with which the same are associated in the manner herein- 25 after to be more fully described.

The operation of my street sweeping machine may be briefly stated as follows—The forward end of the machine is coupled up with the rear end of a tractor or any 30 other vehicle employed for transporting the machine. The brushes are arranged in the manner shown in Figure 2 of the drawing and the scraper blades are positioned so as to engage the ground. As the machine 35 moves along adjacent the gutter, the leaves which have fallen from the trees, as well as any other refuse will be moved by the scraper blades into the path of the brushes and when the scraper 71 is raised to inoper- 40 ative position, the refuse will be collected within the hopper 25 formed by the cooper- ating side brushes 18 and 19 and the rear brush 21. After the hopper has become 45 filled with the refuse, the person occupying the seat 112 on the platform 41 steps on the foot lever 40 causing the spring latches 26 to have the heads on the free ends thereof brought out of engagement with the rear plate 14 and by actuating the hand lever 48, 50 the rear plate and the brush carried thereby is raised to an inoperative position whereby the refuse collected within the chamber 25 will be left in a pile adjacent the gutter to permit the refuse collecting wagon to come 55 along and gather up the same in a simple and efficient manner.

After the plate 14 and the brush 21 carried thereby have passed over the pile of refuse formed by the side brushes, the same 60 is returned to its normal position with respect to the side plate whereupon a refuse collecting hopper is again formed for receiving and forming a pile of refuse at spaced intervals.

65 The lateral movement of the scraper 83

has heretofore been fully explained and the purpose thereof is to provide a means whereby the scraper may be moved toward or away from the curb. It being further understood that the scraper 83 is disposed 70 slightly at an angle as is clearly illustrated in the drawings.

The provision of a street sweeping machine of the above mentioned character, will 75 eliminate the necessity of employing a number of men for cleaning the gutters of refuse as it is only necessary for one person to control the operation of the several parts of the street sweeping machine, and another person for actuating the machine such as the tractor 80 or the like which moves the street sweeping machine along the surface of the ground. When it becomes necessary to make a turn or further when the street sweeping machine 85 is not in operation, the auxiliary frame 4 may be raised to an inoperative position and held therein in the manner heretofore described.

While I have shown the preferred embodiment of my invention, it is to be understood that various changes in the size, shape and arrangement of parts may be resorted to without departing from the spirit of the invention and the scope of the appended 90 claims.

Having thus described the invention, what I claim is:—

1. A street sweeping machine comprising a wheeled main frame, an auxiliary frame 100 hingedly supported on the rear of the main frame, means carried by the auxiliary frame for gathering refuse, said means including side brushes and a rear brush hingedly supported at its upper edge to the rear end of the auxiliary frame, means for raising the 105 rear brush into an inoperative position whereby the refuse collected by the brushes is left in a pile, and means for normally locking the rear brush into cooperative relation with the side brushes.

2. A street sweeping machine comprising a wheeled main frame, an auxiliary frame hingedly supported on the rear of the main frame, means carried by the auxiliary frame for gathering refuse, said means including side brushes and a rear brush hingedly supported at its upper edge to the rear end of the auxiliary frame, means for raising the 115 rear brush into an inoperative position, whereby the refuse collected by the brushes is left in a pile, means for normally locking the rear brush into cooperative relation with the side brushes, said locking means comprising spring catches carried by the side brushes and engaging the adjacent side edges of the rear brush, and manually controlled means for releasing the catches from locking engagement with the rear brush.

3. In a street sweeping machine comprising in combination, a wheeled frame, a 120

refuse gathering and pile forming means at the rear of the frame, a gutter scraper arranged forwardly of said means for moving the refuse in the gutter into the path of the refuse gathering means, a supporting plate for said scraper, a carriage slideable transversely on the frame, means for supporting the plate on said carriage in spaced

relation thereto, means for actuating the carriage, said scraper being vertically slideable on the plate, and means for raising and lowering the scraper with respect to the plate and the carriage.

In testimony whereof I affix my signature.

JOHN M. NEUERT.
